CLAIM

We claim the ornamental design for cultivating garden hoe, as shown and described.

DESCRIPTION

FIG. 1 is a perspective view of cultivating garden hoe showing our new design;

FIG. 2 is the front elevational view thereof;

FIG. 3 is the side view thereof, the opposing side being identical thereto;

FIG. 4 is the back elevational view thereof;

FIG. 5 is the top plan view thereof; and,

FIG. 6 is the bottom view thereof.
